UNITED STATES PATENT OFFICE.

FRANK BOKAN, OF ST. LOUIS, MISSOURI.

KNOCKDOWN BENCH AND TABLE STRUCTURE.

Application filed February 6, 1925. Serial No. 7,252.

My invention relates to knock-down bench and table structures for picnic grounds, parks, halls, meeting places and like places, which when no longer required for their intended purpose, the structures can be readily and quickly disassembled so that a large number of structures can be packed or stored away in piles in comparatively small places in buildings, or other places, and, it is a distinct and practical improvement to overcome certain practical objections to, and defects in, the present types of knock-down bench and table structures.

An object of my invention is to provide carrying frames applicable to either bench or table structures.

A further object is to provide novel means for supporting a back rest when a bench structure is desired.

20 A further object is to provide a cover member usable as a bench seat or table top which is quickly and readily attachable from the carrying frames.

25 A further object is to provide quick detachable bracing means carried by a strengthening rib hinged to the underside of the bench seat or table top member.

30 A still further object of the invention is to provide a novel knock-down bench and table structure, which will possess advantages in points of simplicity, efficiency, durability, and, at the same time prove itself very practical in use and comparatively inexpensive in manufacture.

35 With the above and other objects in view, the invention consists in the novel features of construction, arrangement and combination of parts hereinafter more fully described and finally pointed out in the claims hereto appended.

40 Referring to the accompanying drawings forming a part of this specification, wherein like characters of reference denote similar parts throughout the several views:

45 Fig. 1, is a perspective view of an assembled bench.

Fig. 2, is an end view thereof.

50 Fig. 3, is a perspective view of the shiftable clamping device for the carrying frame legs and back rest supports.

Fig. 4, is a perspective view, partly broken away, showing a center sill attached to the seat body.

55 Fig. 5, is a perspective view of one of the bracing members connecting the seat sill with the carrying, or supporting frames.

Fig. 6, is a detached perspective view of the fixed clamping jaws and their component slideable member.

Fig. 7, is a sectional view of the seat body 60 and sill member in hinged relation.

Fig. 8, is a perspective view of the upper end of one of the back rest supports showing the hook member for supporting a horizontally disposed back rest member. 65

Fig. 9, is a rear view of the back rest member showing the means thereof for attachment with the hook member of the back rest supports.

Fig. 10, is a section through 10—10 of Fig. 70 2, showing the sliding and fastening devices of the angular shaped leg members and the vertical standards.

Fig. 11 is a modified form of Fig. 1, showing the converting features of a bench into 75 a table.

Fig. 12 is a sectional detail view of a table support.

In carrying out the aim of my present invention, I employ a plurality of carrying 80 frame structures 1, each comprising a pair of angularly positioned legs 2 connected by means of horizontally disposed lower and upper rail members 3 and 4, respectively, for rigidly holding each carrying frame structure together and securing it against linear separation. The upper connecting rail 4 of each frame structure 1 is provided in its upper face with a transverse groove, or socket 85 5 adapted to engagingly receive a longitudinally disposed center sill member 6 connected to the underside of a removable seat body 7 by means of suitable hinges 7'. This arrangement prevents lateral displacement 90 of the seat body upon the rails of the carrying frames 1. 95

To more firmly hold the carrying frame members 1 in rigid and spaced alignment with each other, I employ a plurality of brace bars 8, each having the upper beveled end 9. The underside 10 of each brace bar 8 is provided adjacent its upper beveled end with a suitably angular strap bracket 11 for removably connecting the brace bars with the sills 6 by means of suitable fastening devices 12. The opposite or lower ends of the brace bars 8 are each provided with a fastening member 13 fixed in a longitudinally disposed bifurcation 14 thereof. Each fastening member 13 is provided at its free or lower end with a curved or hook shaped end 15 for engagement with an eye member 110

16 secured to the inner face of the connecting rails 3 of the carrying frame 1.

- The reference numeral 17 represents a plurality of back rest supports each having its lower inner face beveled, as at 18, for engagement with the rear face of the rear supporting leg 2 of each carrying frame 1. A pair of suitable U-shaped socket members 19 are fixed in opposed relation to the side faces of the rear legs 2 of each carrying frame 1 and they slidably receive and support the arms of the U-shaped clamp member 20, which have their free ends bent outwardly and away from each other to provide stops 21 to limit rearward sliding movement of the clamp member 20 by coming into engagement with the front faces of the socket members 19. The clamp member 20, it will be observed, provides sockets through which the back rest supports 17 pass and are guided and supported, as shown in Fig. 3. To further guide and support the back rest supports 17, I provide the rear face of the rear leg 2 of each carrying frame 1 adjacent the socket members 19 with an outwardly directed suitable guide pin 22 for sliding engagement in a groove 23 in the beveled face 18 of each back rest support 17, as shown in Fig. 10.
- 30 A back rest rail 24 is removably carried and supported by the back rest supports 17. The back rest rail 24 is provided in its rear face with a cutaway portion and is covered with a plate 26 fixed to the back rest rail 24 by means of suitable fastening devices 27 to provide a socket. Suitably fixed to the front face of each back rest support 17 is an angular bracket or support 28, the upper end of which is receivable in one of the cutaway portions, or sockets 25 of back rest rail for supporting the same holding it against displacement in any direction, excepting upward displacement for removing the back rest rail from its supports.
- 40 45 When the back rest supports 17 are not used, such as when the bench is used as a table, the clamp members 20 are moved forwardly to their closed positions from their rearward or open position, thus they are out of the way of any one seated opposite the rear leg of any of the carrying frames 1.
- In Figures 11 and 12, I have shown a modified form of the invention comprising but a part of the herein described structural elements. In this form of structure, which is suitable for a table, it is optional as to whether the carrying frames have converging legs as shown in Fig. 1, or whether they are in spaced parallel relation, as shown in Figs. 11 and 12. Also it is optional whether or not there is one board 7 employed to act as a table top, or whether there are two boards 7 employed for the purpose as shown in Fig. 11. Also in the table structure, the brace members 8 may be dispensed with
- when desired, as shown in Fig. 11. When there are two boards 7 used for a table top or for a bench seat in lieu of one, it is evident that the rails 4 are each provided with two sills receiving sockets 5 instead of one, as shown in Figs. 1 and 2.
- From the foregoing description, it is evident that the device, when assembled, can be easily and quickly, without the aid of tools, be knocked down or disassembled and the several parts can be individually and advantageously stored in piles in a much smaller space than when the structure is stored in its assembled relation. The knocking-down of the device can be quickly accomplished by first removing the back rest rail 24, then the supports 17, next the brace bars 8 and finally lifting the body or board 7 from engagement with the carrying frames 1. The brace bars 8 being hinged as at 7', it will be observed that one side face of the sill 6 folds into contact with the lower face of board 7 which also causes the brace bars 8 to lie in engagement with the lower face of the board 7 thereby providing a flat unit of the board 7, sill 6 and brace bars 8.
- The assembling of the device is equally as quick and easy as the disassembling of the device, and is readily accomplished by mounting the board 7 upon the spaced carrying frames 1, positioning the supports 17 in the clamps 20 and by attaching the back rest rail to the supports 17. In the table structure, however, the positioning of the back rest supports, the back rest rail and the brace bars are eliminated, thus making it necessary only to mount the board or boards 7 upon the carrying frames.
- The many advantages of the herein described invention will readily suggest themselves to those skilled in the art to which it appertains.
- I do not wish to be understood as having limited myself to the exact details of construction shown and described, but desire to have it understood that the invention I have shown in the drawings is merely illustrative, as it is manifest that various minor changes may be made in the form, shape and particular arrangement of parts without departing from the spirit of my invention, hence I reserve the right to make any such changes, or modifications as may fairly fall within the scope of the appended claim when fairly construed.
- 105 110 115 120 125 130
- What I claim is:
- In a knock down bench and table structure, a plurality of equally spaced supporting leg frames each having a recess in the upper face of the upper member thereof, a board member resting upon the upper member of each supporting leg frame, a rib fixed to the under face of said board member and engaging in the recesses of the upper members of the leg supporting frames, angu-

larly disposed brace members fixed to the underface of the rib, an eyelet fixed to each frame member and each brace member having a curved lower end for engagement with the eyelet of its respective supporting leg frame, a U-shaped socket member fixed to opposite sides of one of the leg members of each supporting leg frame near the upper end thereof, a U-shaped clamp member slid-

ably supported by the U-shaped socket members of each leg frame, a back rest support detachably supported at its lower end by each of said U-shaped clamp members and a back rest rail detachably connected to each of the back rest supports. 10

In testimony whereof, I have hereunto signed my name to the specification.

FRANK BOKAN.
